UNITED STATES PATENT OFFICE.

JACQUES JULES JOSEPH GUILLEMIN, OF CONFLANS-STE-HONORINE, FRANCE.

APPARATUS FOR COATING THE INTERNAL WALL OF PRESERVE BOXES OR TINS WITH METAL FOIL OR PAPER.

Application filed January 14, 1925, Serial No. 2,437, and in France January 21, 1924.

The present invention relates to an apparatus for coating the interior of preserve boxes or tins with aluminium or other metal foil or paper in order to prevent all contact between the contents or preserves and the metal of the said box.

The said apparatus essentially comprises an expanding envelop whose normal diameter is somewhat smaller than the internal diameter of the box, and a mandrel or expanding device of a mechanical, pneumatic or hydraulic nature, controlled by hand, which will apply the said expanding envelop against the inner wall of the box with great force, so that the metal foil which is interposed between the said envelop and the box will adhere to the said internal wall in a permanent manner.

In one embodiment of the invention, the expanding device consists essentially of a pneumatic pump with a metal cylinder or barrel which is surrounded by an indiarubber tube with which it communicates through suitable apertures in its wall, the whole device being disposed within the extensible envelop.

In a second embodiment, the expanding device consists of a cylindrical structure comprising a plurality of segments which are connected together by hinges and can be applied with greater or less force against the expanding envelop within which the said structure is disposed.

In one form of construction, the expanding envelop is composed of a sheet of indiarubber which is strengthened with overlapping edges, the same being disposed within a sheath of thin indiarubber.

The following description with reference to the appended drawings which are given by way of example sets forth the said invention.

Fig. 1 is a vertical axial section of an apparatus according to the invention, employing a pneumatic device, the apparatus being shown in position within the box;

Fig. 2 shows a second apparatus;

Fig. 3 is a section on the line X—X of Fig. 2;

Figs. 4 and 5 show in longitudinal and transverse section a constructional form of the expanding envelop disposed upon the mandrel; and

Fig. 6 shows the said sheath in the expanded state.

As shown in Fig. 1, the said apparatus is engaged in the box 1 and it applies the metal foil or paper against the inner wall of the said box; the extensible envelop 3 is maintained by the indiarubber rings 4 upon the mandrel or expanding device. This latter consists essentially of a pneumatic pump comprising the metallic cylindrical body 5 which has the apertures 6 at the lower part and is surrounded at the exterior by the indiarubber tube 7 which is secured thereto at the top and bottom by suitable binding means 8 and 9. The bottom part of said tube is folded over at 10 in order to ensure the regularity of the pressure exercised upon the said envelop.

The piston 13 is secured to a hollow rod 14 which is apertured at the top at 17 and is provided with a knob 15 for hand control; the said rod traverses the pump cover 16 and fits upon a hollow rod 15^a and having the coaxial position and secured to the bottom of the pump 11, said hollow rod communicating with the box bottom of the holes 12. When the piston 13 is lowered by hand by means of the said knob, the air thus compressed will pass through the holes 6 and will accumulate between the pump cylinder 5 and the indiarubber tube 7; the latter thus expands and applies the said extensible envelop against the box.

The air confined within the said box is discharged at the bottom part and passes through the holes 12 and 17, and the compression of the metal foil 2 by the extensible envelop 3 becomes more and more energetic, until the said foil is finally made to adhere to the bottom of the box; it will then suffice to raise the said piston in order that the envelop 3 will contract and resume its original diameter, so that the apparatus can be removed from the box without interfering with the metal foil.

In the embodiment shown in Figs. 2 and 3, the extensible device consists of a metallic structure which comprises five members 18, 19, 20, 21, 22 which are attached together in suitable places by the hinges 23, 24, 25, 26. The members or segments 18 and 22 are not hinged together, and in the space between the two is inserted a cam 27 pivoted upon a shaft 28 which is rotatable in a bearing 29 (secured to the segment 20) and traverses the tube 30 which is secured to the cover of the apparatus. A rod 14 pro-

vided with the knob 15 is connected with the said shaft by a rod and link mechanism 31, 32.

When the said knob is pressed upon, the 5 said shaft will rotate, thus actuating the cam, which latter will separate the segments 18 and 22, thus expanding the extensible envelop 3. The thickness of the 10 said envelop should be somewhat greater than in the embodiment shown in Fig. 1, and it should be made of a softer material in order that it may be slightly flattened under the pressure which is exercised, so that the 15 metal foil will properly adhere to the surface in spite of any roughness of the surface of the wall.

Figs. 4 and 5 represent a constructional 20 form of the extensible sheath 3 and of the pneumatic mandrel serving for extension purposes. The said sheath consists of an 25 indiarubber sheet 3 which has a canvas or optionally a cardboard backing, said sheet being formed into a cylinder with the slightly overlapping edges 34, 35. The said cylinder is surrounded by a sheath 36 consisting of a thin indiarubber tube which may be secured for instance by cementing the same at 37, according to a generatrix of the cylinder, upon the sheet 3.

80 When the sheet 3 is caused to expand, the outer tube 36 will also expand, and this expansion will take place almost exclusively at the part occupied by the band 36^a, Figs. 6 and 7, so that the said expanding sheath 35 will maintain a continuous periphery in all cases. If the sheet of foil or paper 2 is placed around the said sheath, Figs. 6 and 7, so that the overlapping edges of the foil are disposed against the band 36^a, when 40 the expansion takes place, the sheath 3, 36 will change its shape and will be opened to some extent according to the change of shape or the displacement of the cylinder of metal foil 2, which latter will open and will thus 45 enter into contact with the walls of the box. In this manner, the sheet 2 will be well applied against the wall of the box without formation of folds.

The said expanding sheath may consist 50 simply of an indiarubber cylinder strength-

ened with canvas or otherwise, whereof a band comprised between two generatrices will not be so strengthened. The said band will serve the same purpose as the band 36^a above mentioned.

What I claim is:

1. An apparatus for coating the internal wall of boxes with metal foil or paper, comprising a cylinder, a sheath of extensible material surrounding the said cylinder, 60 means for securing the upper and lower edges of said sheath to the cylinder, an extensible envelop surrounding the said sheath, and means for supplying a fluid between said cylinder and the said sheath in order to 65 expand the said envelop.

2. An apparatus for coating the internal wall of boxes with metal foil or paper, comprising a cylinder forming a pump barrel, a sheath of extensible material surrounding 70 the said cylinder and secured thereto at its upper and lower edges, holes formed in the wall of said cylinder, a piston adapted to supply air between the cylinder and the said sheath, and an extensible envelop surrounding 75 the said sheath.

3. An apparatus for coating the internal wall of boxes with metal foil or paper, comprising a sheet of canvas covered rubber which is formed into a roll with slightly 80 overlapping edges, a thin rubber tube surrounding the said roll of canvas covered rubber, and means for expanding the said rubber tube or extensible sheath.

4. An apparatus for coating the internal 85 wall of boxes with metal foil or paper, comprising an air-pump barrel, a rubber sheath secured to the upper and lower edges of said barrel, a sheet of canvas covered rubber formed into a loose roll or envelop with 90 slightly overlapping edges, a thin rubber tube surrounding the said loose roll, holes formed in the wall of the said pump barrel, and a piston co-operating with said pump barrel and adapted to supply air between the 95 said barrel and the said sheath in order to swell out the said extensible envelop.

In testimony whereof I have signed this specification.

JACQUES JULES JOSEPH GUILLEMIN.
